UNITED STATES PATENT OFFICE.

JAMES H. BISSELL AND CHARLES G. BEAUREGARD, OF TROY, NEW YORK.

FEED-REGULATOR FOR ROAD-SANDING MACHINES.

1,345,120.

Specification of Letters Patent. Patented June 29, 1920.

Application filed May 15, 1917. Serial No. 168,848.

To all whom it may concern:

Be it known that we, JAMES H. BISSELL and CHARLES G. BEAUREGARD, citizens of the United States, residing at Troy, in the 5 county of Rensselaer, State of New York, have invented certain new and useful Improvements in Feed-Regulators for Road-Sanding Machines; and I do hereby declare the following to be a full, clear, and exact 10 description of the invention, such as will enable others skilled in the art to which it appertains to make and use the same.

This invention relates to road-working machines, and has particular reference to 15 machines for distributing sand, gravel, or other like material over a road surface.

The object of the invention is to provide a practicable and complete spreading machine in which provision is made for adjusting the amount of material to be delivered, 20 and also, in which adjustments can be made to permit the regular and proper feeding of materials of different character.

As a more particular object, the invention 25 contemplates the construction of a hopper, having a delivery opening across which is mounted a swinging gateway and a slidable cutoff, whose relationship is such that the area of the delivery opening can be adjusted not only to feed materials in a varying 30 quantity from the hopper, but also to permit the feeding of materials of various kinds past a feed roller, which is mounted below the hopper.

35 With the above objects in view, and such others relating to the details of construction as may hereinafter appear, our invention will now be fully set forth and described, reference being had to the accompanying 40 drawings.

In the drawings:

Figure 1 is a side elevation of the machine,

Fig. 2 is a vertical longitudinal section 45 through the machine,

Fig. 3 is a section on line 3—3 of Fig. 2,

Fig. 4 is a section on line 4—4 of Fig. 2,

Fig. 5 is an enlarged detailed view of a clutch in the driving mechanism,

50 Fig. 6 is a section on line 6—6 of Fig. 5, and

Fig. 7 is an enlarged detailed view.

Referring more particularly to the drawings, 1 represents a horizontally disposed 55 frame-work which is supported upon a running gear which includes the steering wheels

2, and the rear wheels 3. The frame is suitably constructed of angle iron and supports between its side rails, a hopper construction 4. The hopper structure 4, in longitudinal 60 section is V-shaped and is carried by a plurality of vertical standards 5, which, preferably, are also formed of angle iron. The bottom plates 6 and 7, of the hopper, extend from the front and rear, substantially to the 65 middle of the vehicle, but do not meet the lower edge of each plate, being terminated short of the point of convergence of the plates, to provide an opening to which material is delivered from the hopper. 70

The forward bottom plate 7, has across its lower edge a plate 8, which is mounted upon the hinges 9, and in effect continues the bottom plate 7, since its upper surface lies flush with the upper surface of said plate 7. The 75 free end of the plate 8 continues rearwardly in a slightly curved lip 10, which underlies the distributing or feed-roller 11, and mounted against the lower face of the plate 6 in 80 slideable relation thereto is a cutoff gate 12, the latter being adapted to be carried forward in its guideways so that its free end will contact with or may be adjustably spaced from the plate 8. Said cutoff gate 12, has its edges mounted in guideways 13, 85 which are formed by angle bars which are secured in spaced relation to the bottom of the plate 6, so that the latter and the cutoff gate lie in close contact.

The plate 8 has secured transversely across 90 its lower face a lifting bar 14 which extends beyond the longitudinal edges thereof, so that its ends may have secured thereto the extremities of the chains or cables 15, which then pass over the pulleys 16, secured to the 95 sides of the hopper and thence to a winding drum or staff 17, mounted upon the rear of the vehicle and controlled by means of a hand-wheel 18. The cutoff gate 12, has provided on its lower face a plurality of rack 100 bars 19, meshing with the rack bars 19 and the corresponding plurality of pinions 20, which are fixed upon a shaft 21, which extends transversely across the machine and is rotatably mounted upon a pair of brackets 105 22, secured upon opposite sides of the hopper. One end of the shaft 21, is provided with a worm-gear 23, which stands in mesh with a worm 24, on a shaft leading upward below the hopper bottom plate 6, to be operated by a hand-wheel 25 adjacent to the driver's seat 26. A second shaft 21' which 110

is supported in hangers upon the side rails of the frame 1, and supports a series of anti-friction rollers 22', which bear against the lower face of the cutoff gate 12, so as to reduce the frictional engagement of the latter with its guideways.

The distributing or feed roller 11, which has been above mentioned, has its spindle 27, mounted in a pair of brackets or hangers 28, 10 which are secured upon the side rails of the frame 1, the hangers 28 having upright guides in which are mounted blocks 29 borne normally downward by springs 30, upon the tops of the spindles 27, so that the roller 15 is free to rise as necessary when obstructions such as stones are crowded between the periphery of the roller 11 and the lip 10. Mounted upon one end of the roller spindle 27, is a chain sprocket 30, over which extends a drive chain 31, which is also passed over a second sprocket 32, mounted upon the axle of the corresponding rear wheel 3, the arrangement being thus such that the lower portion of the roller 11 is rotated away from 25 the hopper. This sprocket 32, is directly carried upon a slidable hub 33, and has upon its outer face a series of clutch teeth 34, which are adapted to interengage with a corresponding set of teeth which are formed 30 upon a plate 35, secured to the wheel 3. The slidable hub 33 is engaged by a shipper 36, which is formed upon the lower end of a rotatable rod 37, vertically mounted upon the side of the rearmost standard 5, and has 35 a crank 38, by means of which the clutch elements may be engaged or disengaged in order to operate or disconnect the roller 11 from the rear wheel 3. A set of ball-bearings 39, may be placed between the slidable hub 33 and the annular yoke 40, with which the shipper 37, is directly connected, thereby avoiding an undue amount of friction.

The roller 11, has mounted upon its peripheral surface a series of longitudinal ribs 45 41, which adjacent the ends of the roller are bent rearwardly at 42 to throw sand or other material which is fed from the hopper away from the ends of the roller. In its closed position the plate 8, stands at a minimum space or distance from the ribs 41 and 50 42 of the roller 11, and is held at this point by means of stops 43, formed on the hangers 28, against which the extended ends of the rod 14 strike as the plate is brought up to 55 its closed position.

The top of the hopper 4, is normally closed by means of a screen cover, 44, which is secured thereto by means of hinges 45, so that the cover may be swung into or 60 out of position without difficulty.

A suitable steering mechanism is provided for the control of the machine on the road, in that a vertical shaft 46, mounted upon the front of the frame is connected at its lower 65 end to a suitable steering knuckle, and its

upper end is geared to a horizontal shaft 47, whose rear end is provided with a steering wheel 48, adjacent to the driver's seat.

The operation of the foregoing mechanism is apparent from the descriptive matter, but particular attention is called to the possibilities of adjustment whereby materials of various grades may be successfully fed out of the hopper and distributed, and furthermore, the rate of feed may also be regulated, thus a primary adjustment of the device consists in so spacing the lip 10, of the plate 8 from the periphery of the roller 11, that the material which is contained in the hopper will feed freely therebetween. Thus when sand is to be fed through, the roller 11 and the lip 10 of the plate 8 will probably be adjusted to stand at the minimum distance apart, while if the hopper contains the material known as stone dust, a slightly increased distance between the roller and lip 10 of the plate 8 will be necessary, and, obviously, for feeding larger sizes of stone or gravel still wider ranges of adjustment will be required. The ribs 41 and 42, as the roller 11 revolves, throw the material off of the lip 10 of the plate 8, the ribs 42 giving a slight lateral direction to the material as it leaves the roller, so that it will be spread to the proper transverse 80 85 90 95 limits.

The cutoff gate 12, is employed to regulate the quantity of material which may descend to the roller and obviously may be regulated at will by means of the hand wheel 100 25, as hereinbefore described.

It will be observed that the feed from the hopper may be positively controlled or absolutely checked by setting the gate 12; also that when its edge is spaced slightly from the plate 8 so that a little material flows downward over the latter, the material is delivered from the lip 10 by the movement of the ribs across such lip if the roller 11 is rotated; and that the rotation of said roller 110 is controlled by the clutch mechanism. The chain control of the plate 8 adjusts the position of its lip with respect to the roller, according to the grade of material being delivered, and it is possible at any time for the 115 roller to rise so a lump may pass beneath it without retarding or checking the feed.

It will be evident from the foregoing description that we have provided a very complete and practicable feed regulator for a 120 sanding or covering machine which is valuable in connection with the repair of oiled roads after the petroleum has been spread upon the road surface, and an even layer of material may be spread upon the road in 125 practically any desired quantity without waste or undue loss, and with great economy of time and labor.

We claim—

The herein described feed regulator for 130

granular material comprising a hopper having bottom walls converging toward a delivery opening, a plate hinged to the lower edge of one wall and extending across said 5 opening and terminating in a lip, a gate slidably mounted beneath the other wall, means for adjusting it toward and from said plate, a yielding feed roller rotatably supported beneath the gate and having ribs on 10 its surface overlying the lip, and means for

swinging the said plate to adjust the position of its lip with respect to said roller.

In testimony whereof, we affix our signatures in the presence of two witnesses.

JAMES H. BISSELL.

CHARLES G. BEAUREGARD.
